UNITED STATES PATENT OFFICE.

WILLIAM J. NESBITT, OF LOS ANGELES, CALIFORNIA.

HEEL-CUTTING APPARATUS.

1,245,495.

Specification of Letters Patent.

Patented Nov. 6, 1917.

Application filed December 26, 1916. Serial No. 139,046.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus, and I do hereby declare the following to be a full, clear, and exact description of the invention, such as will enable others skilled in the art to which it appertains to make and use the same.

This invention relates to improvements in heel cutting apparatus, and it may be said to consist in the provision of the novel and advantageous features, and in the novel and improved construction, arrangement, and combination of parts as will be apparent from the description and claims which follow hereinafter.

One object of the invention is to provide a novel and improved heel cutting apparatus in which the means for actuating the heel clamping device is also adapted to effect movement of the platform to move the heel against the cutter.

Another object of the invention is to provide a novel and improved heel cutting apparatus which permits of cutting the heel at an angle transversely of the heel.

Other objects and the advantages of the invention will be apparent to those skilled in the art from a careful consideration of the following description of the preferred form of the construction embodying the invention, taken in connection with the accompanying drawings in which—

Figure 1 is a side elevational view of the improved heel cutting apparatus; Fig. 2 is a broken front elevational view taken on the line 2—2 of Fig. 1; Fig. 3 is an elevational view of one of the clamping jaws; Fig. 4 is a plan view of the same; Fig. 5 is an elevational view of the cam for operating the movable jaw of the heel clamping device; Fig. 6 is a plan view of the same; Fig. 7 is a broken enlarged side elevational view of the apparatus; Fig. 8 is a plan view of the same; and Fig. 9 is a side elevational view of the table which carries the heel clamping device.

The supporting frame 10 has thereon the pivot 11 on which is mounted the rear end of the shelf 12. The latter is provided with a dovetail guide 13 which is fitted in a corresponding guideway provided in the under-

side of the platform 14 which is movably mounted on the shelf 12. The platform 14 has thereon a pivot 15 to which is connected one end of the guide 16. The latter is arranged transversely on the platform 14 and is provided with an operating handle 17. The latter has thereon the pivoted latch 18 which is provided with teeth adapted to fit in notches 19 in the rounded end of the lateral extension 20 of the platform 14 so that the guide 16 can be locked in adjusted position on the platform 14.

On the guide 16 is movably mounted the table 21 which carries the heel clamping device. As shown, the table 21 has a slot 22 to clear the top of the pivot 15, and it has a rear extension 23 with the upright projection 24 thereon. On the underside of the table 21 is a guide 25 which is slidably fitted against the rear end of the guide 16.

The cutter 26 is disposed laterally of the shelf 12 and it preferably consists of a bandsaw which passes around the pulleys 27 and 28 which latter are mounted on the shafts 29 and 30, which are journaled in suitable bearings 31 and 32 on the frame 10. Suitable devices indicated at 33 and 34 are mounted on the frame 10 to guide and prevent displacement of the bandsaw 26. As shown, the shaft 29 may be driven by the electric motor 35 which has on its shaft 36 the spur pinion 37 in mesh with the spur wheel 38 on the shaft 29.

The heel clamping device preferably consists of the stationary lower jaw 39 secured to the table 21, and the movable upper jaw 40 which has on its rear the angular arm 41 provided with a pivot 42 which latter is movably fitted in the upright projection 24. The jaws 39 and 40 preferably consist of members adapted to fit in the crease between the heel seat and the heel of a shoe 43 and provided with teeth 44 which are adapted to grip the heel of the shoe 43 when the jaw 40 is moved to engage the heel.

The platform 14 has on one side thereof the pins 45 which pass freely through the slots 46 in the slide plate or cam 47 which latter is provided with a curved lateral extension 48 adapted to contact with the curved lateral extension 49 at the lower end of the arm 41 of the jaw 40. A spring 50 is secured to the upright projection 24 and presses against the lower part of the arm 41 to normally hold the jaw 40 in the raised

position. The slide plate or cam 47 is connected by the pivot 51 to the curved link 52 which is connected by the pivot 53 to the angular lever 54 which is mounted on the 5 pivot 55 at the lower end of the downward extension 56 at the forward end of the shelf 12. A retracting spring 57 is connected between the shelf 12 and the lever 54. An operating handle 58 may be connected to the 10 lever 54; or a foot lever 59 mounted on the pivot 60 on the frame 10 may be pivotally connected to the rod 61 which latter is provided with the knuckle joint 62 and is pivotally connected to the lever 54.

15 The table 21 may be operated by any suitable or approved means, that shown consisting of the handle 63 on the sector 64 which is provided with teeth 65 in mesh with teeth 66 on one end of the guide 16; said 20 sector 64 being mounted on the pivot 67 which is arranged on the forward part of the table 21. A nut 68 on the upper part of the pivot 67 can be turned by means of the handle 69 to lock the table 21 in ad- 25 justed position.

By means of the handle 70 connected to the shelf 12 the latter can be turned on the pivot 11 to swing said shelf, and consequently the heel clamping device, in a vertical plane which is parallel to the plane of the cutter 26, so that the heel of the shoe 43 can be cut at an angle transversely of the heel. The shelf 12 can be locked in adjusted position by means of the latch 71 30 which is mounted on the pivot 72 between the ears 73 on the handle 70 and is provided with teeth adapted to fit in the notches 74 on the frame 10. A spring 75 is arranged between the latch 71 and the handle 70 to 35 normally press the latch into engagement with the notches 74.

From the foregoing description the operation and advantages of the construction will be understood by those skilled in the art. It 40 will be seen that when the heel of the shoe 43 is placed in position on the stationary jaw 39, the handle 63 may be operated to move the table 21 transversely to the cutter 26 according to the amount that is to be cut off of the heel. If it is desired to make an angular cut longitudinally of the heel, the guide 16 is turned in a horizontal plane by means of the handle 17 according to the angle required. If it is desired to make an 45 angular cut transversely of the heel, the shelf 12 is turned in a vertical plane by means of the handle 70 according to the angle required, and thus the heel can be cut to have either side thereof of greater thickness than the other side. By pressing down 50 on the lever 59 or pulling up the handle 58 the lever 54 and link 52 are actuated to move the slide plate or cam 47 and cause the latter to move the arm 41 so that the 55 jaw 40 engages the heel, after which the

pressure on the lever 59 or the pull on the handle 58 causes movement of the platform 14 so that the heel is cut by the bandsaw 26.

The construction which has been particularly illustrated and described admits of 70 changes and modifications, wherefore the right is reserved to all such changes and modifications as do not depart from the spirit and scope of the invention which is defined in the appended claims.

75 I claim:

1. In heel cutting apparatus, the combination of a slidably mounted platform, a cutter, a heel clamping device carried by the platform, and means whereby the platform and heel clamping device can be turned in a vertical plane to dispose the heel so that the cutter will cut the heel at an angle transversely of the heel when the platform is moved.

80 2. In heel cutting apparatus, the combination of a shelf, a platform movably mounted on the shelf, a movable table carried by the platform, a heel clamping device on the table, a cutter, means adapted to turn the 85 table in a horizontal plane to dispose the heel so that the cutter will cut the heel at an angle longitudinally of the heel when the platform is moved, and means adapted to turn the shelf in a vertical plane to dispose the heel so that the cutter will cut the heel at an angle transversely of the heel when the platform is moved.

90 3. In heel cutting apparatus, the combination of a cutter, a support, a pivot on the 95 support, a shelf disposed laterally of said cutter, and a heel clamping device carried by the shelf, said shelf mounted on said pivot so that the shelf can be turned transversely in a vertical plane to dispose the heel to have the cutter cut the heel at an angle transversely of the heel as set forth.

100 4. In heel cutting apparatus, the combination of a cutter, a shelf disposed laterally of said cutter, a heel clamping device carried by the shelf, and a pivot, said shelf being mounted on the pivot so that the heel clamping device can be turned laterally in a vertical plane parallel to the plane of the cutter for the purpose set forth.

105 5. In heel cutting apparatus, the combination of a heel clamping device, a cutter, and a mounting for the heel clamping device which is disposed laterally of the cutter and permits turning of the heel clamping device in a vertical plane parallel to the plane of the cutter for the purpose set forth.

110 6. In heel cutting apparatus, the combination of a movable platform, a heel clamping device carried by the platform, said device 115 including a movable jaw provided with an arm, a cam slidably mounted on the platform, a lever, and operative connections between the cam and the lever so that actuation of the lever causes the cam to move the 120

130

arm to have the jaw engage the heel and then the actuation of the lever effects movement of said platform.

7. In heel cutting apparatus the combination of a movably mounted platform, a heel clamping device carried by the platform, said device including a movable jaw having an arm with a curved lateral extension, pins on the platform, a plate slidably mounted on the pins and having a curved lateral extension in contact with the curved lateral ex-
- 10 tension on the arm, a lever, and operative connections between the plate and the lever so that actuation of the lever causes the plate to move the arm to have the jaw engage the heel and thereupon effect movement of the platform.

In testimony whereof, I have signed my name to this specification at Los Angeles, county of Los Angeles, State of California, 20 this 15th day of December A. D. 1916.

WILLIAM J. NESBITT.
